UNITED STATES PATENT OFFICE.

HENRY G. VOIGHT AND NORMAN B. HURD, OF NEW BRITAIN, CONNECTICUT, AS
SIGNORS TO THE AMERICAN HARDWARE CORPORATION, OF NEW BRITAIN, CON-
NECTICUT, A CORPORATION OF CONNECTICUT.

DOOR-LOCK TRIMMING.

1,024,480.

Specification of Letters Patent. Patented Apr. 23, 1912.

Application filed November 14, 1911. Serial No. 660,264.

To all whom it may concern:

Be it known that we, HENRY G. VOIGHT and NORMAN B. HURD, citizens of the United States, residing at New Britain, county of 5 Hartford, State of Connecticut, have invented certain new and useful Improvements in Door-Lock Trimmings, of which the following is a full, clear, and exact description.

This invention relates to improvements in 10 door lock trimmings.

The object of the present invention is to provide an improved trimming to be used on so-called sanitary doors, the purpose of 15 said trimming being to make a proper finish for a keyhole passage and for knob passages which will lie substantially flush with the door so as to avoid corners and recesses in which dirt and dust can accumulate.

In the drawings, Figure 1 is a side elevation of a part of a door, said view being 20 partly in section, illustrating our invention as applied thereto. Fig. 2 is a vertical section in the plane of the knob in the keyhole, certain parts being in elevation. Figs. 3, 4, 25 5 and 6 each illustrate details of construction.

1 represents a door.

2 represents a knob.

3 represents a key.

30 We will first describe the rose plate or trimming for the knob shank. This rose plate or trimming comprises two members, 4—5. The member 5 is circular in form, having a central threaded recess at its outer 35 side arranged to receive the screw-threaded end of the member 4. In the bottom of the recess in the member 5 and piercing the side wall thereof at as many points as desired (four being shown here) are passages in 40 which are located spurs 6—6. The inner end of the member 4 is preferably beveled, as shown, and arranged to engage the rear ends of the spurs 6—6, the bevel being indicated at 7. As will now be seen, a recess 45 is formed in the door concentric with the axis of the knob 3, said recess being of a depth and size appropriate to receive the member 5 flush with the surface of the door 1. The member 5 is then put in place. The spurs 50 6—6 are then entered and forced radially so as to project into the material of the door 1. These spurs may be forced radially in any desired manner, as by screwing in the member 4 so that the bevel 7 will engage

with the rear ends of the spurs and force 55 them outwardly. When the parts are thus assembled, it will be seen that the surface of the door is substantially flush save for the projection of the member 4 of the trimming. The particular form of retainers may 60 be modified in a variety of ways, the particular form of spur retainers 6—* shown being one improved form. The keyhole trimming may be in the main similarly constructed and applied, said trimming comprising 65 the outer member 5^a and the inner member 4^a, and the spur members 6—6, as in the first instance. The inner member 4^a may be provided with a suitable passage best adapted to receive a key, instead of a knob spindle as in the first instance; for example, said inner member may have a keyhole passage of conventional outline, such as shown in Fig. 4. In both instances it will be seen that the trimming 70 comprises two main parts, one arranged to interlock as by screw-threads with the other, both of said parts having a suitable passage for the particular instrumentality to be employed therewith, be it a key or a knob spindle. In addition to the two elements referred to, the trimming includes movable 75 interlocking devices or means arranged to be forced outwardly or radially into intimate engagement and binding contact with 80 the material of the door so that when the two members are secured in position, the trimming will be complete and will present a severely plain yet handsome appearance which, from a practical standpoint, has a 85 decided advantage over any ornamental trimming which stands wholly above the surface of the door, providing grooves or corners in which dirt may accumulate and from which it is exceedingly difficult to remove such accumulation.

What we claim is:

1. In a door lock trimming of the character described, one member arranged to be sunken in a recess in the surface of a door, 100 a coacting member with means for securing the same to the first mentioned member, holding means carried by the first mentioned member and movable outwardly from the edge thereof to engage with the material of 105 the door to hold the first mentioned member in place.
2. In a door lock trimming of the char-

- acter described, one member arranged to be sunken in a recess in the surface of a door, a coacting member with means for securing the same to the first mentioned member, 5 holding means carried by the first mentioned member and movable outwardly from the edge thereof to engage with the material of the door to hold the first mentioned member in place, said second member coacting with 10 said holding means to hold the same in their operative position when the parts are assembled.
3. In a door lock trimming of the character described, one member arranged to be sunken in the surface of a door, a threaded recess in the outer end of said member, perforations in the side walls of said member, holding devices standing in said perforations and arranged to be moved laterally 15 relatively to the axis of said member, a second member threaded to fit within the threaded recess of said first mentioned member, and arranged to engage said holding de- 20
- 5 vices to hold the latter in their operative positions.
4. In a door lock trimming of the character described, one member arranged to be sunken in the surface of a door, a threaded recess in the outer end of said member, perforations in the side walls of said member, holding devices standing in said perforations and arranged to be moved laterally relatively to the axis of said member, a second member threaded to fit within the threaded recess of said first mentioned member, and arranged to engage said holding devices to hold the latter in their operative positions, said second member being constructed to force said holding devices into operative position. 30 35

Correction in Letters Patent No. 1,024,480.

It is hereby certified that in Letters Patent No. 1,024,480, granted April 23, 1912, upon the application of Henry G. Voight and Norman B. Hurd, of New Britain, Connecticut, for an improvement in "Door-Lock Trimmings," an error appears in the printed specification requiring correction as follows: Page 1, line 62, for the reference-numeral "6—*" read 6—6; and that the said Letters Patent should be read with this correction therein that the same may conform to the record of the case in the Patent Office.

Signed and sealed this 14th day of May, A. D., 1912.

[SEAL.]

C. C. BILLINGS,
Acting Commissioner of Patents.
